UNITED STATES PATENT OFFICE.

JOHN D. HASKELL AND MORTIMER R. RUST, OF FULTON, NEW YORK, ASSIGNEES TO
DILTS MACHINE WORKS INCORPORATED, OF FULTON, NEW YORK, A CORPORATION OF NEW YORK.

PAPER-STOCK STRAINER.

Application filed December 8, 1924. Serial No. 754,626.

This invention relates to a paper stock strainer, technically known as a cylinder washer of the siphon type for beating engines involving the use of a vat or tub in which the mixture of stock and water is circulated by the rotation of the beater roll or any other suitable circulating means for agitating and reducing the stock to the required consistency for manufacturing into paper.

5 During this agitation and circulation a considerable quantity of dirt and other impurities are liberated from the stock and held in more or less suspension in the water and one of the main objects of the present invention is to provide a more efficient and expeditious means for removing these impurities while the fresh, pure water is being added to the mass in circulation and thereby to accelerate the washing or cleansing of the stock

10 20 from such dirt or other impurities.

In other words we have sought to carry out this object by means of a rotary screen drum supported in such manner that a greater or less area of its screened perimeter will project into the vat in the path of movement of the circulating stock to be automatically rotated thereby for successively presenting different portions of the screen in said path and at the same time to cause the dirty or impure water passing through and to the interior of the screen to be automatically withdrawn, preferably by siphon action, as it accumulates therein, while fresh water is being supplied to the vat to replace the impure water as the latter is withdrawn.

25 30 35

Another object is to utilize the flow of fresh water to the vat or tub for starting or assisting the siphoning action.

A further object is to provide means whereby the conduits through which the impure water is withdrawn may be easily and quickly cleansed when necessary or desirable.

Other objects and uses regulating to specific parts of the washing apparatus will be brought out in the following description.

In the drawings:

Figure 1 is a top plan of a portion of a tub or vat in which the stock is circulated together with the rotary screen and a movable support therefor in operative position.

Figure 2 is a side elevation of the parts

shown in Figure 1 except that a portion of the vat or tub is broken away to show the portion of the rotary screen projecting therein.

55 Figure 3 is an enlarged, longitudinal, vertical, sectional view, partly broken away, of portions of the vat and screen and the adjacent portions of the movable supporting frame for the screen together with the means for inducing the siphoning action of the impure water from within the screen.

Figure 4 is an enlarged detailed sectional view of a portion of one end of the rotary screen showing the manner of fastening the 60 peripheral screen to the end heads and connecting bars.

65 In order that the invention may be more clearly understood we have shown a portion of a vat or tub —1— as provided with a 70 lengthwise trough or channel —2— through which the mixture of water and stock is adapted to be circulated in the direction indicated by arrow —a— by any suitable circulating means as, for example, by the roll 75 of a beater engine, not shown, whereby the stock is agitated and reduced more or less to the desired consistency for manufacture into paper.

80 A screen drum —3— which, for convenience of description may be termed a cylinder, is rotatably mounted upon a suitable supporting frame —4— to revolve about a horizontal axis transversely of the channel —2— and extends axially a distance corresponding approximately to the width of said channel with which it is registered and into which the lower side of the cylinder is adapted to project when adjusted for use.

85 90 The frame —4— upon which the screen cylinder —3— is mounted is adjustable vertically for moving the cylinder into and out of the vat and also for varying the depth of immersion of the lower side thereof into the circulating stock in the channel —2—, 95 said frame consisting in this instance of opposite end bars —5— extending diametrically across corresponding ends of the cylinder —3— and beyond diametrically opposite sides thereof and having one end thereof pivoted 100 at —6— to suitable brackets —7— on the upper edges of opposite sides of the vat —1—

while the other ends of the bars —5— are connected to each other by a cross bar —8— to which is connected a hoisting cable —8'— adapted to be connected to any suitable hoisting mechanism, not shown, whereby the frame —4— with the screen cylinder —3— thereon may be rocked about the axis of the bearings —6— to vary the depth of immersion of the lower side of the screen in the liquid stock or by the same hoisting means the screen cylinder may be lifted entirely out of the vat if desired.

The screen cylinder —3— comprises a pair of similar, coaxial end heads —9— arranged in axially spaced relation concentric with the axis of revolution and provided with central hubs —10— which are journalled by means of anti-friction roller bearings —11— upon relatively stationary journal bearings —12— on the central portions of the arms —5— of the frame —4— so that the screen cylinder —3—, as a whole, may revolve freely upon said frame.

These end heads —9— are provided with a plurality of similar openings —13— of relatively large area arranged in uniformly spaced relation, circumferentially about the axis of rotation and are covered by screened panels or discs —14— which are preferably secured to the inner faces of the heads by screws or equivalent fastening means so as to form unitary parts of said heads.

The perimeters of the heads —9— are similarly serrated, the serrations being relatively large or elongated circumferentially to form a series of teeth —15— and depressions —16—, the teeth —15— of each head being arranged in uniformly spaced relation circumferentially and in axial alignment with the teeth of the other head. The edges of the teeth, facing in a direction opposite the direction of rotation of the cylinder —3—, are abruptly inclined at a slight angle to the radial lines passing through the points of the teeth at the side of said radial lines opposite the direction of rotation and are tangential to circles of relatively small radius while the other edges of the teeth are inclined at a much greater angle to said radial lines and are, therefore, tangential to circles of relatively large radius, the joining portions of the long edge of each tooth with the shorter edges of the next adjacent teeth being rounded at —16— to form the depressions previously mentioned and for a purpose hereinafter described in connection with the peripheral screen.

The points of corresponding teeth of the opposite heads —9— are connected by rigid bars —17— which are secured to the heads by screws —17'— or equivalent fastening means so that the outer faces of the bars are substantially coincident with the corresponding points of the teeth.

65 A peripheral screen —18— is wrapped

tightly around and against the peripheral edges of the teeth —15— and are rigidly secured thereto by screws or otherwise to form a unitary part thereof, and to conform to the circumferential outline of the peripheries of the heads —9—.

That is, the ends of the screen —18— follow the peripheral contours of the heads —9— and are supported intermediate the heads by the lengthwise bars —17— to which they are secured by clamping bars —19— which, in turn, are secured to the bars —17— by screws —20— or equivalent fastening means.

It is now clear that when the peripheral screen —18— is wrapped around the peripheral edges of the heads —9— and bars —17— so as to follow the contour of the teeth —15— it will form a circumferentially corrugated perimeter, and the portions thereof which are fastened to the abrupt edges of the teeth will constitute impact faces —21— which when projected into the path of movement of the circulating stock in the vat —1— receive the impact of the moving stock as the latter travels through the channel —2— thereby causing automatic rotation of the screen cylinder.

The corrugating of the screen perimetric of the drum in the manner described produces a series of parallel lengthwise ribs in uniformly spaced relation circumferentially, in which the opposite faces of each rib are disposed at different angles relatively to a radial plane passing through the center of said rib and those having the lesser angle will face in the same direction circumferentially to form the impact faces previously described.

The frame —4— is hung in such manner upon the tub or vat —1— as to swing to a substantial horizontal position close to the upper edge of the vat thus permitting a considerable portion (nearly one-half) of the screen cylinder to be immersed in the circulating water and stock in the channel —2— which allows a considerable quantity of the dirt laden water to pass through the end screens and also through the peripheral screen into the interior of the cylinder where it is adapted to be removed by siphon action in a manner presently described while the circumferentially corrugated peripheral screen adds materially to the screen area exposed to the reception of the water therein all of which greatly increases the washing efficiency of the apparatus and also greatly expedites the washing operation and enables the fresh water to take the place of the impure water practically as fast as it is removed by the siphon action and therefore the stock is practically clean after leaving the washing cylinder.

It will, of course, be understood that any number of these cylinders may be employed to operate in succession along the line of

travel of the water and stock to further increase the washing efficiency and expedition of operation of the machine.

Siphon action.

5 A siphon pipe —22— is extended horizontally through central openings in the end heads —9— of the cylinder —3— and also through aligned openings in the bearings 10 —12— co-axial with the axis of revolution of said cylinder, one end of the siphon pipe —22— being closed by a cap nut —23— while the other end is connected by a T coupling —24— to a radially extending branch pipe 15 —25—, the outer end of the T coupling —24— being normally closed by a plug —26— which may be removed when necessary to allow a suitable cleaning tool to be passed entirely through the pipe —22— for cleaning purposes.

The rear end of the branch pipe —25— is connected to a T coupling —27—, which, in turn, is pivotally connected by a union —28— and a nipple 28' to a 4-way coupling 25 —29—, the axis of the coupling —28— and nipples 28' being co-axial with the axis of the pivots —6— of the screen supporting frame —4— so as to allow said frame with the screen cylinder thereon to rock vertically 30 without straining any of the connecting joints of the siphon system.

The portion of the horizontal siphon pipe —22— within the screen cylinder —3— is provided with one or more T couplings 35 —30— having a radial branch siphon pipe —31— extending downwardly to a level near the lower side of the screen cylinder —3— but in spaced relation thereto and therefore some distance below the level of the liquid 40 stock in the vat —1— when the frame —4— with the screen thereon is adjusted for use so that any suitable degree of suction temporarily created within the coupling —29— and siphon pipes —25—, —22— and —31— will induce an up-flow of the dirty water 45 within the screen cylinder —3— through the pipes —31—, —22— and —25— respectively and thence into the coupling —29— where it may be discharged to a waste pipe or other 50 place of deposit outside of the vat —1—.

A delivery pipe —32— is connected to the lower side of the coupling —29— to extend downwardly therefrom at the exterior of the vat and adapted to be connected to any 55 suitable waste pipe, not shown.

In the use of this siphon principle of education of the dirty water from the interior of the screen, it is, of course, necessary, particularly in starting the siphoning action, to 60 withdraw air from the siphon pipes and inasmuch as it is also necessary to supply fresh water to the vat to replace the dirty water as it is withdrawn the flow of the fresh water to the vat through suitable pipes is utilized 65 for that purpose.

That is, the water from any available source of supply is conducted through a pipe —33— to one end of any suitable air eductor or exhauster —34— having its other end provided with a discharge pipe —35— discharging into the vat, the intermediate portion of said eductor being connected by an air pipe —36— to the upper side of the coupling —29— so that the fresh water under pressure delivered through the eductor will withdraw the air from the siphon pipes —25—, —22— and —31— and thereby induce the flow of water into said siphon pipes and thence out through the discharge pipe —32— whereupon the flow of the dirty water from the interior of the screen will continue under the well-known siphonic action.

70 The pipe —36— is provided with a valve —37— for controlling the suction in the siphon system without in any way affecting the free flow of the fresh water through the pipes —33— and —35— to the vat —1—.

75 The water supply pipe —33— is also provided with a valve —38— which is temporarily opened to start the siphon action, but 80 may be closed after the siphon action begins or when it is desired to prevent excessive supply of water to the vat or over-flow thereof, particularly when the screen cylinder is withdrawn from the liquid stock in the vat —1— 85 by the upward, rocking movement of its supporting frame —4—.

Operation.

During the circulation of the liquid stock 100 in the vat —1— along the channel —2— the frame —4— with the screen cylinder thereon is lowered so that the major portion of the lower half of the screen will be immersed in said stock with its impact faces —21— 105 opposed to the direction of flow of said stock which, in turn, causes a rotary motion of the screen cylinder —3— in the direction indicated by arrow —y—, Figure —2— thereby successively presenting the impact faces to 110 the flowing stock and causing a self-cleansing of the peripheral screen —18— against clogging.

This rotation of the screen cylinder in the liquid stock also causes the stock to be distributed more or less evenly over the screens —18— and —14— and thereby causes a thorough washing of the same from dirt and other impurities and enables the dirty water to pass through the screens into the interior of the cylinder where it is removed by suction through the pipes —31—, —22—, and —25— and discharged to the exterior of the tank through the pipe —32—.

115 Immediately following the lowering of the cylinder —3— into the liquid stock in the vat —1—, the valve —38— is opened to allow the fresh water to flow through the pipes —33— and —35— to the vat —1— and at about the same time the valve —37— is ad-

justed to allow the air to be withdrawn from the suction pipes of the siphon system until the out-flow of the dirty water through said pipes begins, whereupon the valve —37— is 5 adjusted to prevent further suction of the air in the siphon system.

After these adjustments have been made 10 the siphoning of the dirty water from the interior of the screen and the supply of fresh water to the vat —1— to replace the dirty water which is removed continues automatically for an indefinite period of time without any further attention on the part of the operator.

15 What we claim is:—

In a paper stock strainer, a vat having a channel through which the stock is caused to move in one direction, a frame hingedly mounted on the vat to swing vertically about 20 a horizontal axis, a screen drum journaled on the frame to rotate about an axis parallel with and some distance from the axis of movement of said frame, said drum having

its lower side immersed in and actuated by the flowing stock, a siphon pipe extending 25 from the exterior into the interior of the screen drum coaxial with the axis of rotation of said drum and having its outer end provided with a branch pipe extending across the axis of movement of said frame, a siphon 30 discharge pipe, said branch pipe having turning connection with the discharge pipe coaxial with the axis of movement of said frame, an air exhauster connected to one of the siphon pipes, and means for passing water through the exhauster and into the vat for exhausting air from the siphon pipes sufficient to start the siphoning of dirty water from the interior of the drum and for 35 supplying fresh water to the interior of the vat.

In witness whereof we have hereunto set our hands this first day of December, 1924.

JOHN D. HASKELL.
MORTIMER R. RUST.
